Primary Examiner — Lilyana Bekic*Assistant Examiner* — Carson Jean Bendel(74) *Attorney, Agent, or Firm* — Philip Oweimrin(57) **CLAIM**

The ornamental design for a folding trailer with cloth bag, as shown and described.

DESCRIPTION

FIG. 1 is a front perspective view of a folding trailer with cloth bag, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of its folded state thereof;

FIG. 9 is a front view of its folded state thereof;

FIG. 10 is a rear view of its folded state thereof;

FIG. 11 is a left side view of its folded state thereof;

FIG. 12 is a right side of its folded state view thereof;

FIG. 13 is a top view of its folded state thereof; and,

FIG. 14 is a bottom view of its folded state.
